MOLDING DEVICE FOR CONCRETE PILES

Application filed October 7, 1929. Serial No. 398,070.

The present invention relates to an improvement in a molding device for concrete piles and the like comprising a hollow tampering rod adapted to receive a charge of concrete, the hollow rod having a movable section at the lower end thereof adapted to be operated to release and empty the concrete into the pile cavity.

The object of this invention is to obtain a molding device for concrete piles simple in construction and easy to operate, characterized in that the inner tube serves as a tampering rod and concrete can be easily supplied to the pile hole by first filling the inner tube with the concrete and then causing the movable part at the lower end of the inner tube to slide. According to the past experience, the bottom of the inner tube is apt to be damaged by the force required in the first tamping. Now, according to this invention such drawback is removed by fitting a removable reinforcing cap to the bottom of the inner tube in the first tamping only.

Referring to the accompanying drawings, Fig. 1 shows a longitudinal sectional view of this device producing the end of a pile, which expands around it, by tamping the first charge of concrete;

Fig. 2, a cross section of the same;

Fig. 3, a sectional view in which the reinforcing cap has been removed from the lower end of the inner pipe after the operation as illustrated in Fig. 1 and the second charge of concrete has been supplied to the inner pipe;

Fig. 4, a cross section of the same;

Fig. 5, a cross section showing a modification of the fixed and movable parts of the inner tube, and

Fig. 6, a longitudinal sectional view showing the above charge of concrete discharged from the bottom of the movable part into the pile hole by the sliding down of the movable part.

In the drawing, 1 is the outer tube to be driven into the earth, 2 the inner tube which serves as a tampering rod and the lower end of which is divided into two parts as shown at 3 and 4. It is preferable to construct the part 3 so that it is thicker than the tube it-

self and the inner surface of its lower end slightly inclines. The part 4 has a semicircular section formed by dividing the inner tube into two parts and is provided with a thin part 5 formed by cutting away the outer wall of its upper part. This reduced part is inserted in the inner tube 2, so that it can slide along the inner surface of the inner tube 2 and the abutting surface of the part 3. If the movable part 4 is lifted with a suitable rope 10 till its shoulder 6 comes into contact with an abutting end surface 7, the parts 3 and 4 will meet and form a closed tubular vessel, so that if the part 4 is lowered by slackening the rope 10, the concrete contained in the closed vessel will be discharged into the pile hole as shown in Figure 5. 3 and 4 may be formed as shown in Figure 6 instead of Figure 4. That is to say, instead of forming the part 3 thick a guide member 8 may be attached to its either side so as to guide the part 4. 11 is a reinforcing cap to be fitted over the bottom end of the closed vessel composed of the parts 2 and 3 and is fixed to the parts 3 and 4 by means of a rod 13 passing through the cylindrical part 12 of the parts 3 and 4 and the cap 11. A set screw 14 secures the rod 11 in place and is arranged in such a manner that it can be easily fixed or detached.

The operation of the device according to the invention is as follows:

Drive into the earth the outer tube 1 provided with the shoe 15 and pour concrete thereinto. The part 4 is made to meet part 3 to form a closed vessel and the reinforcing cap 11 is fitted on the closed vessel and the inner tube is inserted into the outer tube. Then, tamp the concrete by moving said inner tube up and down, and the shoe 15 will be detached from the outer tube and the concrete will expand in the earth as shown in Figure 1.

After the first operation mentioned above, draw out the inner tube 2 together with the reinforcing cap 11 from the outer tube, take out the rod 13 by turning the set screw 14 and remove said cap, after which the inner tube 2 is again inserted into the outer tube 1 and then is filled with the second charge of

concrete (Figure 3). Next, allow the movable part 4 to slide down by slackening the rope 10, and the concrete will flow down from the inner tube into the pile hole. Pull the rope 10 to make the parts 3 and 4 meet and draw out the outer tube gradually, tamping the concrete with its bottom. Then, it will be possible to produce another knob on the concrete root made by the first operation.

10 If the same operation with the second one is repeated several times, a pile having a number of the knobs or enlargements along its whole length can be obtained.

15 As explained above, the device according to this invention is very simple in construction and easy to operate. Moreover, as the reinforcing cap is used in the first heavy operation, the bottom end, namely the tamping end of the inner tube, is not damaged.

20 Claims:

1. A molding device for concrete piles or the like, comprising a hollow tamping rod adapted to receive a charge of concrete, said hollow rod having its lower end divided longitudinally providing a movable section at the lower end thereof adapted to be operated to release the concrete into the pile cavity.

30 2. A molding device for concrete piles or the like, comprising a tubular tamping member adapted to contain a charge of concrete, said tubular member having an opening in the wall thereof at the lower end, and a movable member closing said opening and adapted to be moved to provide a laterally opening discharge orifice at the lower end of the tubular member for the release of the concrete.

40 3. A molding device for concrete piles, including an inner tube, the lower portion of the inner tube being adapted to be used as a tamping rod and having its lower end divided longitudinally into two sections, one section being slidable along the other so that concrete can be supplied from the bottom of the tube into the hole of the pile.

45 4. A molding device for concrete piles, including an inner tube, the lower end of the inner tube being constituted by two parts arranged side by side, one of which is integral with said tube and the other slidable along the said part so that the concrete can be supplied from the bottom of the tube into the pile hole, the lower ends of the two parts constituting a tamping member.

50 5. A molding device for concrete piles or the like, comprising a hollow tamping rod adapted to receive a charge of concrete, said hollow rod having a movable section at the lower end thereof adapted to be operated to release the concrete into the pile cavity, and a cap member adapted to be detachably secured to the lower end of said hollow rod and

the movable section to protect and reinforce the same during the tamping operation.

6. A device as claimed in claim 5, characterized in that the lower end of the tubular member has its walls thickened to reinforce the same.

7. A molding device for concrete piles, including an inner tube, the lower portion of the inner tube being adapted to be used as a tamping rod and being composed of two sections, one section being slidable along the other so that concrete can be supplied from the bottom of the tube into the hole of the pile, a cap adapted to be fitted over the lower extremity of said tube sections to protect and reinforce the same, and means for detachably securing said cap in place.

8. A device as claimed in claim 5, wherein in the lower end of the hollow rod presents a tapered surface and the cap member is correspondingly tapered.

9. A device as claimed in claim 5, wherein the cap carries an annular flange which encircles the wall of the hollow rod and a fastening pin extending through the cap flange and tube.

10. A molding device for concrete piles and the like, comprising a hollow tamping rod adapted to receive a charge of concrete and having a closed lower end, said rod including a body part having the lower end thereof cut away and a relatively movable part telescopically fitted in the cut away portion of the body part and normally occupying a position with respect thereto to form a tamping implement, said movable part having an external shoulder engageable with the body part to limit the upward movement of the movable part and permit the latter to move downwardly with relation to the body part so as to permit of the discharge of material contained in the rod.

In testimony whereof I have affixed my signature.
